UNITED STATES PATENT OFFICE.

WILLIAM H. SHAFER, OF CINCINNATI, OHIO, ASSIGNOR TO THE AHRENS FIRE ENGINE COMPANY, OF CINCINNATI, OHIO, A CORPORATION OF OHIO.

PUMP.

No. 805,586.

Specification of Letters Patent.

Patented Nov. 28, 1905.

Application filed April 20, 1905. Serial No. 256,627.

To all whom it may concern:

Be it known that I, WILLIAM H. SHAFER, a citizen of the United States, residing at Cincinnati, Ohio, have invented a new and useful Improvement in Pumps, of which the following is a specification.

My invention relates to pumps of the duplex double-acting class adapted to use in fire-engines and elsewhere; and the objects of my improvement are to place certain valves in recesses formed in the channels to prevent them from obstructing the currents, to locate the supply-openings in an unobstructed line, to form the different chambers on curved lines to avoid conflicting currents, and to dispose the various chambers in a single integral structure in such manner as to obtain maximum capacity and efficiency with the most compact, rigid, and durable form of construction. These objects are attained in the following-described manner, as illustrated in the accompanying drawings, in which—

Figure 1 is a plan, with parts in section, on the line *xx* of Figs. 2 and 3, of a pump of the designated class embodying my improvements; Fig. 2, a vertical section on the line *aa* of Figs. 3 and 4; Fig. 3, a front elevation, with parts broken away and parts in section, on the line *yy* of Fig. 4; and Fig. 4, a plan, with the head removed and parts in section, on the line *zz* of Fig. 3.

In the drawings, the pump-body 5 consists of intersecting vertical cylinders 6 and 7, formed integral with each other and with discharge-chamber 8. The cylinders are provided with removable heads 9 and 11 and the chamber 8 with removable front wall 12. Said chamber is formed with discharge-openings 13 in its opposite ends each adapted to the engagement of a hose therewith and with a central top opening 14, which communicates with an ordinary air-chamber. (Not shown.) Parallel partitions 15 and 16, formed within the cylinders, terminate in vertical wall 17, parallel with and joined to the rear wall 18 of the discharge-chamber by a narrow middle partition 19. They separate the common suction-chamber 21 from the independent top and bottom pulsation-chambers 22 and 23, located in the ends of the cylinders on opposite sides of the middle wall 24. Pump-barrels 25, concentric with the respective cylinders, are each provided with a plunger 26, which may be reciprocated therein in the usual manner by

means of a duplex engine, (not shown,) preferably having "quartering" strokes. They each extend through the suction-chamber and terminate in open ends within corresponding pulsation-chambers.

Recesses or offsets 20 are formed in partitions 15 and 16 on one side of the throat or channel 27 of the respective pulsation-chambers which lead to the discharge-chamber through the corresponding groups of valved openings 28, formed in rear wall 18. Valved openings 29 within said recesses do not choke or obstruct the respective channels 27, and, together with valved openings 31, they are disposed in circles concentric with the respective ends of the pump-barrels and lead from the suction-chamber to the respective pulsation-chambers through partitions 15 and 16. Supply-pipes 32, in registration with each other, are each adapted to the engagement therewith of a suction-hose and formed with an opening 34, which communicates with an ordinary vacuum-chamber. (Not shown.) They communicate with the rear portion 35 of the suction-chamber on a line tangent to the pump-barrels to avoid any obstruction thereby to admission of the water to the interior of the suction-chamber. Hand-actuated emergency-valve 36 serves to open or close passage 37 between the suction and discharge chambers.

In operation the downward movement of either plunger draws the water through the appropriate circle of valved openings from the suction to the corresponding top pulsation-chamber and simultaneously drives the water from the corresponding bottom pulsation-chamber through the corresponding group of valved openings to the interior of the discharge-chamber. The upward movement of either plunger in like manner fills the corresponding bottom pulsation-chamber and simultaneously drives the water from the top pulsation-chamber to the interior of the discharge-chamber. Either plunger may be actuated independently of the other, but by synchronizing the strokes quartering the most constant stream will be maintained through the discharge-chamber. The pump-barrels do not obstruct the admission of water to the suction-chamber nor the valves in the recesses its passage to the discharge-chamber, whereby increased valve area is obtained. The cylindrical walls of the suction and pul-

sation chambers facilitate the movement of water therein and obviate counter currents. The smallest increase in the efficiency of pumps of this class which will cause them to 5 perform increased duties and surpass the high standard of excellence of the present state of the art adds greatly to their value and desirability.

What I claim as my invention, and desire to

10 secure by Letters Patent, is—

1. The combination of a suction-chamber, a pulsation-chamber, a partition between them having valved openings in different parallel planes, a pump-barrel provided with a plunger, a discharge-chamber having a discharge-opening and separated from the pulsation-chamber by a valved partition, and an emergency-valve in said partition.

2. The combination of a substantially cylindrical body, parallel partitions therein each having valved openings in different parallel planes and separating a middle suction-chamber from top and bottom pulsation-chambers, a pump-barrel extending through the suction-chamber concentric with the body and terminating in open ends within the respective pulsation-chambers, a reciprocating plunger therein, a supply-pipe communicating with the suction-chamber on a line tangent to the 25 pump-barrel, a discharge-chamber and a vertical partition having groups of valved openings leading thereto from the respective pulsation-chambers.

3. The combination of a body formed of 30 two intersecting cylinders, a discharge-chamber integral therewith, pump-barrels concen-

tric with the cylinders, plungers therein, valved partitions separating from a common suction-chamber, pulsation-chambers communicating with the respective ends of each 40 barrel, valved offsets formed in the partitions channels leading from the respective offsets to the discharge-chamber, a valved partition adjacent to the offsets and parallel with the barrels separating the pulsation-chambers 45 from the discharge-chamber.

4. In a pump, the combination of a body, a barrel therein, and a valved partition extending between them and formed with different valved portions in parallel planes, for the 50 purpose specified.

5. A pump of the designated class having in combination a body, a barrel therein, a valved partition extending between the body and the barrel and a valved offset formed 55 therein and in a plane parallel therewith, for the purpose specified.

6. A pump of the designated class having in combination, a cylindrical body, a concentric barrel therein parallel valved partitions 60 extending between the body and the respective ends of the barrel, said partitions being each formed with a valved offset in registration with the other and in a plane parallel therewith, whereby increased valve area is 65 obtained without interfering with the passage of water to the discharge-chamber from the pulsation-chambers.

WILLIAM H. SHAFER.
